UNITED STATES PATENT OFFICE.

CHARLES B. FLETCHER, OF ST. LOUIS, MISSOURI.

DESIGN FOR A HORN CHAIR.

SPECIFICATION forming part of Design No. 12,490, dated September 27, 1881.

Application filed August 22, 1881. Term of patent 7 years.

To all whom it may concern:

Be it known that I, CHARLES B. FLETCHER, of St. Louis, Missouri, have invented a new and Improved Design for a Horn Chair, of which the following is a full, clear, and exact description.

In the accompanying drawing, forming a part of this specification, a perspective view of my newly-designed horn chair is shown.

- 10 The back of the chair is formed of two horns, A, attached to the side of the seat C and united at their points, and thus forming an arch or bow, which horns A are braced by two horns, B, extending from the middle of the rear of the seat 15 C and extending outward and upward to the horns A, thus intersecting the arch. Arm-rests are formed of horns D, attached to the front end of the seat C and extending upward and backward to the horns A. Horns E are attached 20 to the seat between the bases of the horns A and B, and extend frontward and upward to the horns A. The leg of the seat is formed of four or more horns, F, united at the bases and extending outward and downward, the pointed 25 ends of the horns resting on the floor. The horns are highly finished and polished, and are so arranged that opposite horns will have the same curvature. The horns preferred are ox or cow horns; but any other similar horns can 30 be used in place of the ox or cow horns. The points of all the horns forming the back of the chair project upward, and the points of the

horns forming the leg project downward. The lower ends of the horns A, or the wooden stocks to which they are attached, are surrounded by 35 fabric H, and a row of metal tacks with ornamental heads are driven into the horn at the top of the fabric.

Having thus fully described my invention, I claim as new and desire to secure by Design 40 Patent—

1. The design for the back of a horn chair herein shown and described, consisting of horns A, forming an arch intersected by horns B B, as set forth.

2. The design for the back of a horn chair herein shown and described, consisting of horns A, forming an arch intersected by horns B B, the horns A being braced by front and rear horns, D and E, as set forth.

3. The design for the back of a horn chair herein shown and described, consisting of horns A, forming an arch, and surrounded at the lower end by fabric H, and by a row, J, of metal buttons, as set forth.

4. The design for the leg or base of a horn chair herein shown and described, the same consisting of four horns united at the thicker ends and spreading outward and downward, as set forth.

CHARLES B. FLETCHER.
